DESIGN FOR A DRESS

Tora Coleman, New York, N. Y.

Application November 27, 1936, Serial No. 66,160

Term of patent 3½ years

To all whom it may concern:

Be it known that I, Tora Coleman, a citizen of the Republic of Latvia, residing at No. 301 East 38th Street, city of New York, Borough of Manhattan, county of New York, and State of New York, have invented a new, original, and ornamental Design for a Dress, of which the following is a specification, reference being had to the accompanying drawing, forming a part thereof.

Figure 1 is the front view of a dress embodying my design.

Figure 2 is the back view thereof.

The characteristic feature of the design consists of a crossed yoke and tucked shoulders and back, having bands of different colors along the front extending from the crossed portions of the yoke to the bottom, giving the appearance of an inverted pleat as shown. The ascot scarf at the neck forms part of the design.

I claim:

The ornamental design for a dress, as shown and described.

TORA COLEMAN.
